DRAWING-OUT NEEDLE FOR USE IN MACHINES FOR DRAWING OUT THREADS FROM
TISSUES

Application filed November 2, 1927, Serial No. 230,510, and in Germany September 8, 1926.

Drawing-out needles used in machines for drawing out threads from tissues and having the shape of a wedgelike sawblade toothed at both its edges, are already known heretofore. Said needles require the use of a separate pricker for the purpose of preparing the threads of the tissue for the subsequent application of the drawing-out needle and thereby preventing an unintended removal of false threads.

From this known art, the present invention is distinguished by the drawing-out needle being at its lower extremity formed like a pricker, that is wedge-shaped at its rear part and fitted at its rear top end with a downwardly inclined projection, for the purpose hereinafter set forth.

The accompanying drawing illustrates the improved drawing-out needle in Figs. 1 and 2 in a front view and in a side view respectively.

The drawing-out needle *d* is toothed at its lower edges *e* and beyond the latter extended to form at its lower extremity an integral pricker *a*, of which the rear part *b* is wedge-shaped while its rear top end facing the lower toothed-edges of the needle forms a downwardly inclined projection *c* thereon.

When using the needle, the threads of the tissue are parted by the pricker *a* and the cross-threads are forced back by the wedge *b*, so that the teeth *e* of the needle *d* can reliably grip the longitudinal threads and force the same downwards. By the inclined projection *c* on the pricker *a* any cross-threads which might have been pressed down are again lifted, so that at the moment of cutting they are located beyond the path of the cutter of the machine.

The improved needle has the advantage that a separate picker is dispensed with, the drawing-out of the threads can be effected in a reliable manner, and a cutting-off of cross-threads is securely prevented.

What I claim, is:—

The combination with a drawing-out needle for use in machines for drawing-out threads from tissues having serrated wedge-shaped tapering edges, of an extension on the

lower wedge shaped portion of said needle serving as a pricker upwardly inclined towards the rear side of the needle, and of an inclined projection on the upper edge of said extension adapted to lift any pressed-down threads. 55

In testimony whereof I have hereunto set my hand.

KARL MISCHKE.
